CLAIM

The ornamental design for a weightlifting wrap, as shown and described.

DESCRIPTION

FIG. 1 is a front view of a weightlifting wrap illustrating my new design;

FIG. 2 is a rear view thereof;

FIG. 3 is a left side elevational view thereof, the right side elevational view is a mirror image of FIG. 3;

FIG. 4 is a front end view thereof, the back end view is a mirror image of FIG. 4;

FIG. 5 is an enlarged front view showing detail of the ornamental aspects of the design; and,

FIG. 6 is an enlarged rear view showing detail of the ornamental aspects of the design.

The broken lines in FIGS. 1 and 2 are for the purpose of illustrating the cut lines of the enlarged views of FIGS. 5 and 6, respectively.
